(57) **CLAIM**

We claim the ornamental design for a cover for ceiling ventilation fan, as shown and described.

DESCRIPTION

FIG. 1 is a perspective view of a cover for ceiling ventilation fan of the present invention;

FIG. 2 is a front elevation view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line **8-8** of FIG. 2.**1 Claim, 8 Drawing Sheets**8 ←

FIG. 1

FIG. 2

FIG. 3

FIG. 4

FIG. 5

FIG. 6

FIG. 7

FIG. 8
